MECHANISM FOR REMOVING CONES FROM MOLDS AND TRIMMING SAME.

1,247,090.

Specification of Letters Patent. Patented Nov. 20, 1917.

Application filed February 16, 1917. Serial No. 149,051.

To all whom it may concern:

Be it known that I, ALBERT E. DIETERICH, residing at Washington, in the District of Columbia, have invented certain new and 5 useful Improvements in Mechanism for Removing Cones from Molds and Trimming the Same, of which the following is a specification.

There has heretofore been devised a new 10 construction of cone molding and baking mechanism with means for receiving the cone from the mold which consists of a mechanism for holding the baked cones in a relatively stationary position after the cores 15 are loosened (and removed, if desired) and during the initial part of the opening movement of the female mold sections, and secondly, of a device which is projected between the partly separated female mold sections 20 to receive or embrace the cones and hold them against following the female mold sections as the said sections continue separation for the purpose of releasing the cones from the molds and from the holding device, 25 and thirdly, a method of extracting the cones from the molds, which method consists in holding the cones against movement during the initial part of the opening act of the female molds to strip the cones loose from 30 the moving parts of the female molds and subsequently holding the cones while the prior holding device is separated from the cones and then removing the cones from their location between the female mold parts. 35 The female mold sections of the mechanism referred to have separable parts, certain of which open up in advance of the others, the latter serving to hold the cones stationary while the former separate from the cones 40 during the initial opening movement of the molds, but which latter devices separate or leave the cones as soon as the receiver has been projected between the initially separated parts of the female molds to embrace 45 the cones and restrain them from following the mold parts when completing the opening and releasing act.

My invention relates especially to the machine such as contains the structure, aforesaid, and it has for its object to provide a modification of the said mechanism whereby all danger of breaking the cone in freeing it from the last-to-open-parts of the female molds, is avoided. Another object of my invention is to provide a trimming mechanism 55

with stationary trimmer tubes, as in the Bruckman type of machine (see Patent #1,071,027, of August 26, 1913, for example) with which the invention is especially useful, and to provide a positive means 60 for conveying or lowering the cone from the female mold region into the trimmer tubes whereby each individual cone will be positively set into its respective trimmer tube member in a position ready for the pusher, 65 which forces the cone through the tube to trim off the excess batter or "heads."

Generically, then my invention comprises a reciprocated receiver that moves through the trimmer tubes up between the partly 70 separated female molds and snugly embraces the exposed part of the cone and when the female molds are fully open the receiver descends again through the trimmer tube leaving the cone hanging in the trimmer tube 75 by its excess batter-head, after which it is pushed through the tube either by a pivoted pusher (as hereinafter shown and described) or by the shuttle type of pusher that forms the subject of my Patent No. 1,216,292, issued February 20, 1917. 80

More subordinately, the present invention includes a receding chute that is located below the trimmer tubes and above the receiver, by which chute the trimmed cones 85 are shot to the off-take conveyer (not shown) of the machine, the receding chute member being adapted to be moved out of the way automatically by the receiver as the receiver is raised and passes through its active cycle 90 of movement.

The invention also includes those novel details of construction, combination and arrangement of parts, all of which is first fully described, then specifically pointed out 95 in the appended claims and illustrated in the accompanying drawings, in which:

Figure 1 is a section and part elevation illustrating the invention.

Fig. 2 is a transverse vertical section taken 100 substantially on the line 2-2 of Fig. 1, the core being shown in place and a baked cone ready for delivery from the molds, the trimmer mechanism and the receiver mechanism being in the inactive position. 105

Fig. 3 is a view similar to Fig. 2 showing the position of the parts just after the receiver has been moved up to embrace the cone after the female molds are partly open and before the final opening movement has 110

occurred, the core being indicated as withdrawn.

In the drawings, in which like numerals and letters of reference indicate like parts in all of the figures, 1 represents the rotary wheel (when the invention is used in the Bruckman type of machine) on which the arms 2 that support the female mold halves 3 are located, it being understood that the 10 arms 2 in the Bruckman type of machine are pivoted to open the female mold sections with a pivotal movement. Each female mold section includes the matching half-cone cavities 4 and they also support 15 the oven sides 5, the oven being covered by a top 17 carried by the core members 16 that are secured to the core bar 18.

In the prior construction, before referred to, the female mold cavities are recessed, as 20 at 6, to receive ring-like holders that embrace the mouth of the cone and their inner surfaces form a continuation of the molding surfaces of the molds when the parts are in the normal or closed position. The half-ring members 7 are respectively mounted 25 on bars 9 that operate through slots 8 in the female mold sections and have collars 10 between which and bearings 12 coil springs 11 are located to continuously tend 30 to force the rings 7 together, the bearings 12 being carried on brackets 15 that are secured to the wheel frame 1. 13 are collars and 14 are stop pins whereby the movement of the rods 9, under the influence of 35 the spring 11, is limited.

19 designates the trimmer tubes of which there is one tubular section for each mold cavity of the female molds and the trimmer tubes 19 may be, *per se*, of any approved 40 construction. They are mounted on brackets 20 which connect the vertical channelways 23 with the standards or supports 21, the supports 21 and the channelways 23 being bracketed to the connecting ring 22 on which 45 the mold opening and closing cams (not shown) are usually mounted. 24 is another brace securing the guideway 23 to the standard 21 and also serving to support standards 29 in which the chute section supporting rock shaft 30 is journaled, the rock 50 shaft 30 carrying arms 31 which are moved in one direction by spring action 32 and which are connected by members 33 with the yieldable chute section, the section 34 fitting 55 into the upper stationary section 26 that is secured at 27 to brackets 25 pendent from the trimmer tube unit and the yieldable section 34 of the chute also engages the lower fixed section 28 which is secured at 28^a to 60 the standards 21.

35 is the arm of the pusher which is pivoted at 36 and carries the tube engaging member 37, the arm 35 being connected by a rod 40 with the bell crank 38, the latter 65 being pivoted at 39 and adapted to be op-

erated by a quick-throw-cam 41 on the cam shaft 42.

43 is a reciprocating frame having guides 44 operating in the guideways 23 and supporting tubular bodies 45, one for each molding section, the tubes 45 having conical receivers 46 at their upper ends and being of a diameter to pass through the respective trimmer tube sections 19 and enter between the partly open female molds (see Fig. 3) to receive the cone just prior to the release of the same, as the rings 7 open up.

The frame 43 may be reciprocated by any approved type of mechanism, such for instance, as that shown in the drawings, and this mechanism comprises a support 47 on which is fulcrumed a long lever 48 that has a pin and slot connection 49 with the frame 43.

50 is a stud on which a lever 51 is fulcrumed and has a pin and slot connection 52 with the lever 48. 53 is an arm fulcrumed on the lever 51 and having a recess 56 for the roller 55 on the end of one arm of the bell crank 54, which is also pivoted 90 on the stud 50 and is spring connected at 57 with the arm 53, the construction being such that in the event that the frame 43 is obstructed in its movement, no motion will be imparted to the lever 48 by the 95 rocking of the bell crank 54, as the end 55 of the bell crank will ride out of the recess 56 against the spring tension 57 and the lever 48 be prevented from moving. The bell crank 54 is operated by a cam 58 on 100 the cam shaft 42.

In operation, assume the parts to be positioned as shown in Figs. 1 and 2: the mold having arrived at the extraction or delivery station, and the mold opening devices, (not shown) just about to begin opening. As soon as the female mold sections have opened to the extent indicated in Fig. 3, the cam 58 will have rocked the bell crank 54 to raise the lever 48 and thus elevate the frame 110 43 with the tubes 45. As the upper ends of the tubes 45 engage the yieldable chute section 34, it will be swung to the position shown in Fig. 3, and the tubes 45 will pass through the trimmer tubes 19 to bring the receivers 46 into position between the partly separated female molds and around the cone therein, as clearly shown in Fig. 3 of the drawings. As soon as the ring members 7 are separated by the further opening of the 115 female molds, which occurs immediately after the tubes 45 have reached the position indicated in Fig. 3, the cone will be released from the rings 7 and held in the receiver 46, which, immediately the release of the 120 cone from the ring 7 is effected, returns to the position shown in Fig. 2, thus leaving the cone hanging by the excess batter or "head" (see dotted lines Fig. 2) in the trimmer tube. As soon as the receiver 46 has 125 130

reached the position shown in Fig. 2, the cam 41 will rock the bell crank 38 to bring the pusher head 37 down on the cone and force it through the trimmer tube 19, whereupon it drops onto the chute and is conveyed to the off-take mechanism, the pusher then being restored to its initial position by the action of the spring 35.

In this application, I make no claim to 10 the construction of the molds, *per se*, nor to the broad combination of such molds with a receiver that is designed to enter between the partly open female molds for the purpose of holding the cone while the rings 7 15 separate, as that forms the subject-matter of the application of Alexander McLaren, hereinbefore referred to, nor do I lay any claim, *per se*, to the particular mechanism shown for raising and lowering the frame 20 43, as that mechanism, *per se*, forms a part of the mechanism for operating core greasers in the patent of Frederick A. Bruckman, granted December 1, 1914, No. 1,119,239.

From the foregoing description, taken in 25 connection with the accompanying drawings, it is thought the complete construction, operation and advantages of my invention will be readily understood by those skilled in the art.

30 What I claim is:

1. In a mechanism of the class described, a pair of separable female mold members, a core therefor, a cone holder for holding the cone stationary during the initial separation of the female mold members to release the cone from the separated parts, means for releasing the holder, a stationary trimmer tube, a cone receiver and conveyer designed to be projected through the trimmer tube and between the partly separated female mold members to receive and retain the cone while the holder is released to free the cone from the holder, and means for projecting and retracting said receiver whereby the cone will be deposited in the receiver while projected and brought from the molds into the trimmer tube during its retracting movement.

2. In a mechanism of the class described, 50 a pair of separable female mold members, a core therefor, a cone holder for holding the cone stationary during the initial separation of the female mold members to release the cone from the separated parts, means for releasing the holder, a stationary trimmer tube, a cone receiver and conveyer designed to be projected through the trimmer tube and between the partly separated female mold members to receive and retain 55 the cone while the holder is released to free the cone from the holder, means for projecting and retracting said receiver whereby the cone will be deposited in the receiver while projected and brought from the molds into 60 the trimmer tube during its retracting move-

ment, and means for pushing the cone from the trimmer tube to effect the trimming act.

3. In combination with the molding devices each comprising male and separable female mold parts, and with the trimming 70 mechanism which includes a trimmer tube, of a cone receiver and means to project said receiver through said trimmer tube and between the female mold parts when sufficiently separated, and to again lower the receiver whereby the cone will "hang" in the trimmed tube for trimming purposes, if necessary.

4. The combination with the molding devices, the trimming mechanism beneath the 80 same which includes a trimmer tube, of an off-take chute including a movable section, a cone receiver, and means for reciprocating said receiver to displace said chute and project through said trimmer tube into proximity with the molding devices to receive the cones from said molding devices and deliver the same into the trimmer tubes.

5. In a machine of the character described 90 having a pair of separable female mold sections, a core therefor, and means for opening and closing the several mold members; a cone holder independent of the core for holding the cones separated from the molds during the initial part of the opening act; 95 a cone receiver; means for projecting the receiver between the partly open female mold members to embrace the cone before the holder is operated to release the cone; a trimming mechanism including a trimmer 100 tube through which said cone receiver is projected and retracted whereby to convey the cone from the mold into the trimmer tube to be trimmed.

6. In a machine of the character described 105 having a pair of separable female mold sections, a core therefor, and means for opening and closing the several mold members; a cone holder independent of the core for holding the cones separated from the molds 110 during the initial part of the opening act; a cone receiver; means for projecting the receiver between the partly open female mold members to embrace the cone before the holder is operated to release the cone; in 115 combination with a trimming mechanism including a trimmer tube into which the cone is deposited by said cone receiver as it recedes from between the mold sections.

7. In a machine of the character described 120 having a pair of separable female mold sections, a core therefor, and means for opening and closing the several mold members; a cone holder independent of the core for holding the cones separated from the 125 molds during the initial part of the opening act; a cone receiver; means for projecting the receiver between the partly open female mold members to embrace the cone before the holder is operated to release the 130

- cone; said cone receiver having a conical cone receptacle that closely conforms to the cone which it is desired to receive, and means for removing the cone from the receiver.
5. In a machine of the character described having a pair of separable female mold sections, a core therefor, and means for opening and closing the several mold members; a cone holder independent of the core for holding the cones separated from the molds during the initial part of the opening act; a cone receiver, means for projecting the receiver between the partly open female mold members to embrace the cone before the holder is operated to release the cone; said cone receiver having a conical cone receptacle that closely conforms to the cone which it is desired to receive, and means for lifting the cone from the receiver and trimming the cone.
9. In a machine of the character described having a pair of separable female mold sections, a core therefor, and means for opening and closing the several mold members; a cone holder independent of the core for holding the cones separated from the molds during the initial part of the opening act; a cone receiver, means for projecting the receiver between the partly open female mold members to embrace the cone before the holder is operated to release the cone; said cone receiver having a conical cone receptacle that closely conforms to the cone which it is desired to receive, and a tube through which said receiver passes, said tube conforming closely to the diameter of said receiver and through which tube said receiver recedes whereby said tube will remove the cone from the receiver.
40. 10. In a machine of the character described having a pair of separable female mold sections, a core therefor, and means for opening and closing the several mold members; a cone holder independent of the core for holding the cones separated from the molds during the initial part of the opening act; a cone receiver, means for projecting the receiver between the partly open female mold members to embrace the cone before the holder is operated to release the cone; said cone receiver having a conical cone receptacle that closely conforms to the cone which it is desired to receive, a trimming mechanism including a trimmer tube
- through which said receiver passes, said tube conforming closely to the diameter of said receiver and through which tube said receiver recedes whereby said tube will remove the cone from the receiver.
11. In a mechanism of the class described, molding devices which include separable female mold sections and cores therefor, a trimmer tube below the mold sections, a pusher for pushing the cones through said tube, an offtake chute, a cone receiver, and mechanism for moving said receiver into position with relation to the molding devices for the reception of the cone while it is being disengaged from the molding devices and for delivering the cone to the trimmer tube to be trimmed.
12. In a machine of the class described, molding devices which include separable female mold sections and cores therefor, a trimmer tube below the mold sections, a pusher for pushing the cones through said tube, an offtake chute, a cone receiver, and mechanism for moving said receiver into position with relation to the molding devices for the reception of the cone while it is being discharged from the molding devices and for delivering the cone to the trimmer tube to be trimmed, said receiver comprising a member adapted to engage said chute and cause it to recede while said receiver is moved up through the trimmer tube into juxtaposition with the molding mechanism.
13. In a mechanism of the class described, molding devices which include separable female mold sections and core therefor, a trimmer tube below the mold sections, a pusher for pushing the cones through said tube, an off-take chute, a cone receiver, mechanism for moving said receiver into position with relation to the molding devices for the reception of the cone while it is being discharged from the molding devices and for delivering the cone to the trimmer tube to be trimmed, said receiver comprising a member adapted to engage said chute and cause it to recede while said receiver is moved up through the trimmer tube into juxtaposition with the molding mechanism, and a chute restoring device operating to return said chute into place after said receiver disengages the same.

ALBERT E. DIETERICH.
